ELECTRICAL TRANSMISSION SYSTEM

William George Harding, Whitton, and Robert Hayes Nisbet, Osterley, England, assignors to Sperry Gyroscope Company, Inc., Brooklyn, N. Y., a corporation of New York

Application May 4, 1938, Serial No. 206,088
In Great Britain May 7, 1937

4 Claims. (Cl. 172—239)

The present invention relates to systems for transmitting indications from a sensitive indicator, such as a gyro or magnetic compass, to a number of remote points.

In accordance with the present invention, an electrical transmission system comprises a step-by-step transmitter or A. C. "Selsyn" transmitter the electrical indications or signals provided by which are amplified by electric or electromagnetic means to serve to actuate a receiver.

In order that the present invention may be more fully understood, various embodiments thereof will now be described with reference to the accompanying drawings, in which—

Fig. 1 is a circuit diagram of a system according to the invention employing a half-wave rectification circuit;

Fig. 2 is a circuit diagram of a similar system, but wherein full-wave rectification is employed;

Fig. 3 is a circuit diagram of a three-line step-by-step transmission system;

Fig. 4 illustrates one arrangement of a pair of grid-controlled rectifiers for use in the circuit of Fig. 3;

Fig. 5 illustrates an alternative arrangement to that of Fig. 4;

Fig. 6 illustrates a transmitter suitable for use in the circuit of Fig. 4 or Fig. 5;

Fig. 7 is a circuit diagram of a three-line step-by-step system similar to that of Fig. 3 but wherein the "delta" arrangement of the rectifiers is replaced by a "star" arrangement thereof;

Fig. 8 illustrates a dynamo-generator 4-line system for amplifying D. C. step-by-step signals, embodying the invention;

Fig. 9 illustrates a system similar to that of Fig. 8 but providing a 3-line system;

Fig. 10 is a diagram of an alternative arrangement to that of Fig. 9, showing the several generators combined into one;

Fig. 11 is a circuit diagram of an electrical 3-line "Selsyn" transmission with follow-up control.

Referring first to Fig. 1, reference numerals 1, 2, 3 denote grid-controlled gas-discharge rectifier tubes, the cathodes 4, 5, 6 of which are connected together and to terminal 7 of the secondary winding of a transformer 8 the primary winding of which is connected to a source of alternating current. The other terminal 9 of transformer 8 is connected to the anodes 10, 11, 12 of the tubes 1, 2, 3 through impedances 13, 14, 15 respectively.

The cathodes 4, 5, 6 of the grid-controlled 55 12 to the star-connected windings A', B', C' of

rectifiers are also connected to a tapping-point 16 on a resistance 17 connected across a source of direct current so that the cathodes are positive with respect to the leg 18 of the D. C. supply.

5 The grids of the three tubes are connected respectively to tapping points 19, 20, 21 on resistances 22, 23, 24, each of which has one end connected to the negative leg 18 of the D. C. supply, while their other ends are connected respectively to common side contact fingers of the contact gaps 25, 26, 27. The contact fingers of the other side of the contact gaps are all connected to the positive leg 28 of the D. C. supply.

If the contact gap 25 is open, the grid of tube 15 1 is at the same potential as the negative leg of the D. C. supply, whereas the cathode is connected to point 16 which is more positive than this. The tapping-point 16 is so selected that the grid of tube 1 is sufficiently negative in these circumstances with respect to the cathode 4 to prevent current from passing. When the contact gap 25 is closed, the resistance 22 is connected across the D. C. supply, and the tapping-point 19 is at once made positive with respect to the negative leg 18.

10 The position of the tapping point 19 is so chosen that, when the contact gap 25 is closed, the potential of the point 19, and therefore that of the grid of tube 1, becomes positive with respect to the cathode 4, so that the tube becomes conductive. Rectified current then flows from terminal 9 of transformer 8 through impedance 13, thus producing a difference of potential, having both D. C. and A. C. components, across impedance 13. This difference of potential may act as a source of supply to apparatus connected across impedance 13.

15 The contactor gaps 25, 26, 27, having pairs of contact fingers denoted by the letters A, B, C, represent the contacts of a four-line step-by-step transmitter of well-known type for transmitting movements such as the relative turning of the follow-up element of a gyro-compass and a ship. The transmitter is connected so as to be operated by the turning movement in question, and,

20 45 when so operated, it closes the contact gaps 25, 26, 27 in succession in the following recurring sequence for continuous motion in one sense, i. e., the contact fingers are closed in succession in the following order: A, AB, B, BC, C, CA. It follows that the tubes 1, 2, 3 become energised 50 in the corresponding sequence and therefore that voltages are produced across the impedances 13, 14, 15 in this sequence.

25 55 Connections are taken from the anodes 10, 11, 12 to the star-connected windings A', B', C' of

repeaters, one of which is shown at 29; the star-points of the repeaters are connected to the common point 9' of the impedances 13, 14, 15. Windings A', B', C' are therefore subjected to whatever voltages are developed across impedances 13, 14, 15 so that, under the conditions assumed, they are energised in the recurring sequence: A', A'B', B', B'C', C', C'A', just as if they had been connected directly to the correspondingly lettered transmitter contact gaps 25, 26, 27. The energisation of the windings therefore produces a magnetic field in the repeater 29 that rotates in steps thus causing the armature, which may be polarised or unpolarised, to follow this field by rotating in a step-by-step manner.

With the system of the present invention it is possible to operate a large number of repeaters such as 29, since the tubes 1, 2, 3 can handle quite large currents. In spite of this, the resistances 22, 23, 24 can be very high, so that not more than a few milliamps need be handled by the transmitter contacts 25, 26, 27; sparking and burning of the latter are therefore prevented.

Since the voltages across impedances 13, 14, 15 have A. C. and D. C. components, the currents flowing in the windings A', B', C', of the repeaters 29, etc., will have A. C. and D. C. components. If desired, the alternating current components may be filtered out by the use of filter circuits. Since the windings A', B', C' are inductive it may be found sufficient for this purpose to by-pass the windings by condensers, or, what amounts to the same thing, to include condensers as circuit elements in parallel with the impedances 13, 14, 15. However, a certain amount of A. C. in the windings A', B', C' is advantageous. Thus, when the supply of current ceases in winding A' owing to the breaking of the gap 25, there will be current in either winding B' or C'; if this current has A. C. components these will affect the core of winding A' and help to demagnetise it more effectively than would occur by the mere cessation of current in winding A'. The operation of the repeater 29 is therefore more definite and accurate at high speeds with A. C. and D. C. than with D. C. alone.

If desired, therefore, all filtering may be dispensed with, in which case the impedances 13, 14, 15 in parallel with the windings A', B', C' of the repeaters 29, etc. may be omitted from the circuit.

Full-wave rectification circuits may be employed instead of the half-wave rectification circuit shown in Fig. 1. In Fig. 2 there is shown an arrangement in which the circuits for tube 1 of Fig. 1 are replaced by full-wave rectification circuits employing two tubes 1' and 1''. As shown, two separate D. C. supplies 18', 28', and 18'', 28'' are required for supplying the grid voltages for tubes 1' and 1'' respectively; these may be obtained from additional secondary windings on the transformer 8 by the aid of rectifiers. Similarly the contact gaps 25' and 25'' (which need to be operated simultaneously to give full-wave rectification) must be separate: the system therefore requires 6 transmitter contacts operating in pairs. This result may be obtained by using two transmitters arranged to operate corresponding contacts simultaneously.

A somewhat similar method of amplification may be employed for the three-line step-by-step transmission system in which the repeater coils are energised in either direction, i. e., either positively or negatively. The principle of this method is shown in Fig. 3 in which the repeater 30 is

of the standard type for this system of transmission, the stator having three coils connected in delta formation. The transmitter 31 is represented as including three arms containing rectifiers also connected in delta formation the vertices being the points 32, 33, 34. Each arm of the transmitter contains two branches with rectifiers, such as A₁ and A₂, which are connected between the points 33, 34.

10 The rectifier A₁ is adapted, when excited by means described hereinafter, to drive current from 33 to 34; similarly the rectifier A₂ is adapted, when correctly excited, to drive current from 34 to 33. Rectifiers B₁B₂C₁C₂ are similarly 15 adapted to drive current in one direction, the directions of the currents produced by A₁B₁C₁ being clockwise around the transmitter and those produced by A₂B₂C₂ being anti-clockwise.

In Fig. 4 A₁ and A₂ are shown as grid-controlled rectifier tubes, the cathodes of which are supplied from winding 37 of transformer 38 and winding 39 of transformer 40 respectively. Both rectifiers are supplied from the centre-tapped winding 41, 42 of transformer 40, the primary winding 43 of which is connected to an A. C. supply. The winding 41 is connected between point 33 and the anode of A₁ while the winding 42 is connected between point 33 and the cathode of A₂. Point 34 is connected to the cathode of A₁ and to the anode of A₂. There are thus two branch paths between 33 and 34 each containing a secondary winding of transformer 40 and a rectifier tube. The branch containing A₁ is therefore adapted to pass current from 33 to 34 or else to interrupt such current according to the manner in which the grid of A₁ is excited, while the branch containing A₂ is adapted to pass current from 34 to 33 or else to interrupt such current according to the manner in which the grid of A₂ is excited. Fig. 4 thus illustrates how the arrangements illustrated schematically in Fig. 3 may be practically embodied.

The grid circuits for controlling the rectifiers are also shown in Fig. 4. Transformer 38 has a tapped secondary winding 45, the tapping point being connected to the centre-tap of the cathode winding 37 of tube A₁. Winding 45 is connected to the grid of A₁ through an impedance 46 so as normally to apply a grid voltage in opposite phase to the anode voltage, whereby the tube A₁ is normally non-conductive. However, when the transmitter contact 47 is closed the grid of A₁ is directly connected to the end of transformer winding 44 thus giving the grid an opposite voltage so that the tube becomes conducting.

Fig. 5 shows an alternative arrangement for the grid control of rectifier tubes arranged in a circuit similar to that of Fig. 4. The grid of tube A₁ is connected to the cathode supply winding 37 of transformer 38 through the secondary windings 48 and 45 of transformers 49 and 38 respectively each secondary winding being shunted by a resistance to keep the grid-cathode-circuit impedance low. Transformer winding 45 supplies a grid voltage in opposite phase to the anode voltage so as to extinguish the tube when no voltage is applied by transformer 49.

The primary winding 50 of transformer 49 is in series with the secondary winding of transformer 51 and with transmitter contact 47 so that, when this contact is closed an A. C. voltage is introduced into the grid circuit of tube A₁ by the secondary winding 48. This voltage is in phase with the anode voltage and is of sufficient magnitude to overcome the voltage ap-

plied by transformer 38 and render the tube conducting.

It is obvious that the tube A₁ would be extinguished not merely if transformer 49 is applying no voltage to the grid circuit but also if it is applying a voltage in opposite phase to the anode voltage. Consequently a variation of the circuit of Fig. 5 may be employed in which transformer 49 sometimes applies an in-phase voltage, sometimes no voltage and sometimes an out-of-phase voltage to the grid of A₁, the anode voltage of A₁ being taken as reference. The six tubes A₁A₂B₁B₂C₁C₂ can therefore be made conductive in any desired sequence by closing the grid contacts in that order.

In order to obtain the sequence of steps of energisation for the windings of the repeater 30 normal for this repeater during turning of the transmitter in one direction, the tubes must be operated in the sequence:

A₁, A₁B₂, B₂, B₂C₁, C₁, C₁A₂, A₂, A₂B₁, B₁, B₁C₂, C₂, C₂A₁. This results in current flowing in any one coil in repeater 30 for periods of five steps in each direction with one intermediate step of zero current between periods.

In the arrangement of Fig. 4 six separate transmitter contact pairs are required, and there are no two contacts that are in direct electrical connection. Twelve lines are therefore required from the transmitter. Fig. 6 illustrates a transmitter contact arrangement in which the number of contacts to be operated is considerably reduced. In this figure the transmitter consists of three similar cams 52, 53, 54 angularly spaced apart 120° on a single shaft. Rotation of the cam shaft causes cam 52 to oscillate a finger carrying a contact 55 so as to cause 55 to contact alternately with two contact stops 56, 57, with intermediate periods during which 55 contacts with neither of stops 56, 57. Contact stops 56, 57 are connected to opposite ends of the secondary winding 58 of transformer 59, the primary winding of which is connected to the A. C. supply. The primary windings of two transformers 60, 61 are connected in parallel between contact finger 55 and the centre-point of winding 58. It follows that the transformers 60, 61 are energised simultaneously by voltages in phase with the A. C. supply or in phase-opposition thereto according as finger 55 makes contact stop 56 or 57. Transformer 60 controls tube A₁, acting in the same manner as transformer 49 in Fig. 5 while transformer 61 controls tube A₂.

Each of the cams 53, 54 operates a finger in the same manner as does cam 52 in order to control tubes B₁B₂C₁C₂ of Fig. 3.

The contacts 55, 56 and 57 produce three conditions of energization of the pair of tubes A₁ and A₂. In the first condition, contacts 55, 56 are closed, so that transformers 60 and 61 are energized from the upper half of secondary winding 58. It is plain that the transformers 60 and 61 may be so connected in the grid circuits of the tubes A₁ and A₂ that A₁ is made conducting and A₂ non-conducting. In the second condition, the transformers 60 and 61 are energized in the opposite sense from the first condition so that A₂ is made conducting and A₁ non-conducting. In the third condition, neither contact is made and the grids of tubes A₁ and A₂ are subjected only to whatever permanent bias voltages are applied, e. g., by transformer windings such as 46. In Fig. 4, this bias is in the sense that makes the tubes non-conducting.

The conditions of operation required are that, 75

in a transmitter cycle of twelve steps, each tube should be conducting for three steps, which is ensured if the pair of contacts 55 and 56 make for three steps and the pair of contacts 55 and 57 for three steps, with intervening gaps of three steps on each side in which neither pair of contacts is made.

Since all the voltages in Fig. 4 are in-phase or in direct phase-opposition to each other it is evident that the transformers 38 and 40 need not be independent transformers but can be replaced by a single transformer with separate secondary windings. Furthermore, it is clear that, as the anode voltages of all the tubes are in-phase or in phase-opposition with each other, the voltages required to energize the grids of all the valves are in phase or in phase-opposition with each other, so that all the grid-operating voltages may be derived from the same transformer 59. It has been shown that the voltages for tubes A₁ and A₂ can be obtained from the finger 55 oscillating between contact stops 56, 57, connected to this transformer. The contact stops for the fingers operated by the cams 53, 54 for controlling the remaining tubes can therefore be electrically connected to stops 56, 57. The transmitter therefore requires only 5 electrical connections, one for each of the three fingers and two for the two sets of three contact stops.

Fig. 7 shows an alternative circuit arrangement equivalent to that of Fig. 3, the three pairs of rectifiers such as A₁A₂ being connected in star formation instead of in delta formation. The circuit details of Figs. 4, 5 or 6 may be used in this arrangement, except that the sequence of energisation must be somewhat different from that suitable for Fig. 3.

The system of Fig. 7 requires that current must flow from 31 to 34 for five transmission steps and from 34 to 31 for five transmission steps, and that there must be, between each group of five steps, an interval of one transmission step during which no current flows in the branch between 31 and 34. In order to obtain this result, A₁ must be energised positively (to make it conductive) and A₂ negatively by a signal of five steps' duration; this must be followed by an interval of one step during which no signal is applied to A₁ or A₂; there must then follow an interval of five steps during which A₂ is energised positively and A₁ negatively; and, finally, to complete the cycle, there must be another interval of one step during which neither A₁ nor A₂ is energised. The correct cycle of operation can be provided by a transmitter and circuit similar in all respects to those shown in Fig. 6, with the exception, however, that the contacts require to be differently adjusted so that the angle through which each finger remains in contact on any one contact stop is 150°.

Commutator transmitters of standard types with brushes or rollers may also be used for this purpose. In particular the commutator transmitter of British Patent No. 470,001 (filed January 30, 1936) is suitable.

In contrast with the systems of amplification described above, in which thermionic amplifiers are employed there will now be described some systems employing dynamo generators as amplifiers. In these systems a constantly-running motor drives one or more generators excited by currents from the master transmitter, whereupon the generators generate voltages proportional to the signals from the master transmitter.

It has previously been proposed to employ a

transmitter, the signals from which controlled the excitation of a generator whose output was led to receivers. In these systems, however, the transmitter signals were direct currents as long as the transmitter was stationary and the generator generated corresponding D. C. voltages which were applied to synchronous motors acting as the receivers. The receivers had continuously wound stators, and the currents supplied by the generator excited a constant magnetic field, the direction of whose axis was determined by the position of the transmitter.

In such systems, the position of rest of the receiver is defined entirely by the relative magnitudes of the currents in the windings, and not by any permanent structure of the magnetic field such as slots or salient poles. The transmission system in which these receivers were used was usually provided with a transmitter designed to change very gradually with rotation the output currents that it provided, so that the receivers turned continuously and smoothly. However, to effect this, these systems had the disadvantage that the positions of rest of the receivers were not sharply defined so that the indications were appreciably altered by friction or by other disturbing torques.

We refer to such systems as graduated transmission systems since the magnetic structure of the receiver stator is such as to permit graduated and continuous rotation and we refer to them as graduated D. C. systems because the currents supplied to the receivers are direct currents when the transmitters are not rotating.

Step-by-step transmission, in which at every step full current is switched into or out of a winding of a receiver having sharply defined or salient poles, gives very much sharper definition to the position taken up by the receiver motor. Each characteristic position is therefore reproduced accurately and with considerable torque, and for many purposes this accuracy is more important than smoothness of motion.

In circumstances where smoothness of motion is of importance A. C. transmission possesses advantages as compared with graduated D. C. transmission. Both are graduated in their action but the signals for D. C. transmission are provided by a potentiometer or by brushes movable on the commutator of a rotating electrodynamic machine, and there are always present contact or commutation troubles which are much more serious than any experienced with the slip rings of A. C. transmitters or receivers. In addition, the circuits employed are inductive, so that lags in operation are obtained with D. C. transmission. Finally, residual magnetism causes quite appreciable errors in a graduated D. C. repeater, whereas the alternating currents used in A. C. transmission are completely free from this source of error.

The previously proposed graduated D. C. transmission system cannot therefore entirely replace either the D. C. step-by-step transmission systems or the graduated A. C. systems. Both of the latter two systems are in extensive use and it is frequently necessary to enlarge an existing installation of either type so that a larger number of receivers can be driven than was initially contemplated.

According to the present invention, we provide means for supplying a large number of receivers (or a heavily loaded receiver) either of the step-by-step type or of A. C. type with currents for positioning the same, said means comprising a

constantly running generator whose output is controlled by excitation currents supplied or controlled by a transmitter.

Fig. 8 illustrates an embodiment of the invention as applied to a D. C. step-by-step transmission system. In this figure the three D. C. generators 62, 63, 64 on a common shaft are driven by a motor 65 which has its armature and field winding 66 both supplied from a D. C. source. The field windings 67, 68, 69 of the generators 62, 63, 64 are supplied from the same D. C. source, the negative leg being connected to all three windings but the positive leg being connected only through the transmitter 70. The latter has three contact segments 71, 72, 73 on which rest two angularly spaced contact brushes 74, 75, both connected to the positive leg of the D. C. supply. As the transmitter rotates brushes 74, 75 make contact with the contact segments 71, 72, 73 thus exciting the windings 67, 68, 69 in sequence alternately singly and in pairs. As the field winding of each generator is energised, an E. M. F. is generated in its armature: these E. M. F.'s are proportional to the currents produced in the field windings by the transmitter 70 and they may therefore be used to produce, in external load circuits connected to them, amplified versions of these currents. For this purpose the negative brushes of the three generators are connected together and connected to the negative line 76 of the outgoing transmission system, while the three positive brushes are each connected to one of the lines 77, 78, 79. These four lines leading to repeaters therefore provide four-line step-by-step transmission of the same well-known type as that provided by transmitter 70. Fig. 9 illustrates a similar method of amplification for step-by-step transmission of the 3-line D. C. type. The transmitter 70' has three contact segments 71', 72', 73', as in the construction of Fig. 8, but these segments are energised from a rotatable carriage having two pairs of brushes or rollers 74', 75' and 74'', 75''. The contacts 74', 75' are angularly spaced and are connected together to the negative leg of the D. C. supply, while the contacts 74'', 75'' are connected to the positive leg. When the transmitter rotates, the three segments 71', 72', 73' are therefore each energised alternately positively and negatively from the D. C. supply. The field windings 67', 68', 69' of generators 62', 63', 64' are connected in star formation between the lines running from the three segments 71', 72', 73' and are thus energised alternately positively and negatively. Corresponding E. M. F.'s are generated in the armature windings which are also connected in star formation across the lines 77', 78', 79' leading to the repeaters. The generators 62', 63', 64' generate voltages proportional to those applied to their field windings and therefore produce voltages across the lines 77', 78', 79', corresponding to those developed on the contact segments 71', 72', 73'; in other words amplified transmission signals are sent out along the lines 77', 78', 79'. Fig. 10 illustrates a variation of the arrangement shown in Fig. 9 in which the three generators 62', 63', 64' of that figure are replaced by a single generator 86 having a fully wound stator the windings of which are closed and resemble those of a three-phase induction motor. The three transmitter segments 71', 72', 73' are connected to equidistant tapping points on the stator winding so that the three segments 67'', 68'', 69'' of the windings correspond to the field windings

67', 68', 69' of Fig. 9 except that they are connected in delta formation instead of in star formation. The rotor has a commutator connected to a similar closed winding and three brushes 80, 81, 82, spaced 120° apart rest on the commutator in such positions that the voltages between the pairs of brushes are proportional to the excitation currents in the windings 67', 68', 69'.

The brushes 80, 81, 82 are connected to the output transmission lines 77', 78', 79' through compensating windings 83, 84, 85 on the stator. These windings are intended to neutralize the field set up on the rotor by the armature currents drawn from the brushes 80, 81, 82, respectively, to supply the lines 77', 78', 79', so that the fields produced by the windings 67', 68', 69' are not distorted thereby.

A generator of the type shown at 86 is also suitable for use as an amplifier for "Selsyn" A. C. transmission signals. In such a system the transmitter may be a "Selsyn" transmitter of the usual type, or may be a commutator, potentiometer, or other type of transmitter capable of generating suitable currents for positioning "Selsyn" receivers. The generator 86 of Fig. 10 may also be used to amplify signals proceeding from a "Selsyn" transmitter.

Fig. 11 shows a system of transmission in which electrical amplification of signals is associated with a follow-up system. The element 99 is the one from which transmission is to be effected, but instead of gearing a transmitter to this, a follow-up element 100 is provided, and a two-part controller 101, 102. The latter is preferably of the inductive or balanced variable-gap transformer type described in U. S. Patent No. 1,959,804 to B. A. Wittkuhns et al., dated May 22, 1934, in which the member 101 is an iron armature lying symmetrically in the field of a three-legged transformer core 102. The centre leg of this core carries the primary winding which is energised from a source of alternating current and two secondary windings connected in series opposition are disposed on the outer legs. The output of these two secondary windings in series is suitable for the control of a servo-motor, as is explained in U. S. Patent 2,054,945 to R. H. Nisbet, dated September 22, 1936. The output is passed to the amplifier 103 which controls the servo-motor 104 to run in one direction or the other according to the sense of the displacement of member 99 relative to member 100, e. g., in the manner explained in U. S. Patents 1,959,804 and 2,054,945 above-mentioned. On the shaft of the servo-motor 104 is fixed a carriage 105 carrying two contact rollers or brushes 106, 107 connected to slip rings 108, 109 by which current is led in from an A. C. supply 110. The rollers or brushes 106, 107 make contact with the potentiometer winding 111, from which connections 112, 113, 114 are taken at three fixed equally spaced tapping points. These connections lead to an amplifying generator 115 similar to that shown in Fig. 10. The output of generator 115 is taken by the three lines 116, 117, 118, to "Selsyn" repeaters, one of which is shown at 119. The primary windings of the "Selsyns," e. g., winding 120, are supplied with single-phase currents from a generator 121 on the same shaft as generator 115 and driven from the same motor 122.

The armature 123 of "Selsyn" 119 is geared to the follow-up member 100 that follows the member 99. This connection constitutes the follow-

up or repeat-back connection from servo-motor 104 to the controller 101, 102 for this servo-motor, as will now be explained.

If member 99 moves, the two-part controller applies an input to the amplifier 103 thus causing motor 104 to run in a direction corresponding to that in which member 99 has moved. The carriage 105 rotates causing changes in the voltages applied to lines 112, 113, 114. This in turn causes changes in the voltages applied by the generator 115 to lines 116, 117, 118 so that all the repeaters turn by corresponding amounts. In particular, repeater 119 turns the rotor 123 driving the follow-up member 100 to follow member 99. The servo-motor 104 runs until the follow-up member 100 overtakes the member 99 at which point the output of the two-part controller 101, 102, to the amplifier 103 falls to zero, and the motor 104 stops. It is to be remarked that in this system all errors in amplification due for example to the voltages picked off the potentiometer 111 being non-proportional to the angle of turn of brushes 106, 107, or due to the E. M. F.'s generated by generator 115 being non-proportional to the currents in the excitation windings, are automatically neutralized by this system. The motor 104 runs until repeater 119 is correctly matched with member 99; the transmission signals along lines 116, 117, 118 are therefore correct, since the repeater 119 is positioned by them, the motor 104 being controlled to run so as to take out inherent errors. It follows that all the other repeaters actuated by the transmission signals in lines 116, 117, 118 also become correct.

It is well known that gyro-compasses require a follow-up member from which transmission may be effected. When the system of Fig. 11 is used for transmission from a gyro-compass, the member 99 may be taken as representing the sensitive element of the compass. The member 100 must therefore be a member that follows up the sensitive element so as to control servo-motor 104 to cause the correct transmission signals to be sent out. The follow-up member 100 may be additional to any follow-up member already present in the compass: alternatively it may be the sole follow-up member and serve all the purposes of the so-called "phantom element" which acts as a suspension for the sensitive element in a well-known type of compass. In either case, the following member 100 follows the sensitive element 99 of the gyro-compass and therefore all the repeaters are subject to the "north steaming error" of the gyro-compass. In order that the repeaters should be corrected, a corrector may be used at the gyro-compass so that the part 101 of the two part controller is displaced by the correct amount relative to the sensitive element to correct the error, or so that the part 102 is displaced relatively to the part 100 by this amount. Correctors for automatically varying correction as the ship changes course are shown in U. S. Patents 2,110,766 to W. G. Harding, dated March 8, 1938, and 2,128,559 to W. G. Harding et al., dated August 30, 1938. An alternative method of introducing corrections is to do so in the supply lines to the rotor 123 of "Selsyn" 119, in which case the corrector mechanism could be operated by a repeater motor remote from the compass, e. g., one supplied from the lines 116, 117, 118.

For this purpose, the connections supplying the "Selsyn" secondary windings 123 would be taken, not from the lines 116, 117, 118, but from the secondary windings of a "Selsyn" differen-

tial (not shown), whose primary windings were supplied from the lines 116, 117, 118. The corrector would produce relative angular movement of the stator and rotor of this "Selsyn" differential and thus introduce the required correction.

Having now particularly described and ascertained the nature of our said invention and in what manner the same is to be performed, we declare that what we claim is:

1. In a positional control system having a controlling element and a controlled element, intermediate control means comprising a plurality of grid controlled gas discharge rectifier tubes having grid and plate circuits, an A. C. supply for said plate circuits, an independently adjustable source of potential connected to each of said grid circuits, contact means arranged to be actuated in definite sequence by said controlling element and connected to adjust said grid circuit potentials in a manner causing currents to flow in similar sequence in the respective plate circuits of said tubes, and a motor having a stator and a rotor, said rotor being connected to position said controlled element and one of said motor members having windings respectively connected to the plate circuits of said tubes to be energized by currents therein, the position assumed by said rotor being determined by the energized winding or windings.

2. A positional control system as defined in claim 1, wherein said grid controlled rectifier

tubes are arranged in pairs in parallel, the two tubes of a pair being adapted to pass current in opposite directions.

3. A positional control system as defined in claim 1, wherein said grid controlled rectifier tubes are arranged in pairs in parallel, the two tubes of a pair being adapted to pass current in opposite directions, means for biasing both tubes of a pair so that the same are normally non-conducting, said contact means being so actuated that opposite control potentials are applied to the grids of the two tubes, whereby only one tube of a pair is rendered conductive at a time.

4. In a D. C. step by step transmission system having a controlling element, a controlled element and a multi-pole motor for positioning said controlled element at discrete positions corresponding respectively to the energized pole or poles, a source of alternating current, a plurality of rectifier tubes having control grids and having their outputs respectively connected to energize said motor poles, circuit means for energizing the plate circuit of said tubes from said A. C. source, a source of direct current, a transmitter adapted to apply potentials derived from said D. C. source to the grids of said tubes, in sequence, individually and in pairs, for energizing the respectively connected poles of said motor.
